(57) **ABSTRACT**

A new variety of *Citrus* plant named 'Mikanken15' that has dark orange fruit color, without seeds, high juiciness, orange-like flavor, ease of peeling the fruit by hand, good appearance, and good tasting qualities.

3 Drawing Sheets

1

Common name: Mandarin.
Botanical classification: *Citrus* spp.
Variety denomination: 'Mikanken15'.

BACKGROUND OF THE NEW VARIETY

The present invention relates to a new and distinct variety of Mandarin, *Citrus* spp., which has been given the variety denomination 'Mikanken15'.

ORIGIN OF THE VARIETY

The parent varieties are 'HAREHIME' (female parent) (not patented in the U.S., plant variety protection granted in Japan, PVP No. 1,209) and 'Ehime17' (male parent) (not patented in the U.S. nor in other countries), respectively.

The variety was developed and propagated in Uwajima, Ehime, Japan.

The variety was reproduced asexually by vegetative reproduction by top grafting one-year-old scions on rootstocks. The rootstock used was 'MIYAGAWAWASE' (not patented in the U.S. nor in other countries) as an interstock grafted onto *Poncirus trifoliata* (trifoliate orange).

In 2005, crossing the parent varieties.

In 2006, collected seeds were grown.

In 2008, they were grafted on top of rootstock.

In 2010, the first fruit was harvested.

In 2012, lines were primary selected and secondary selected, and the variety was named 'Mikanken15'.

In 2024, Breeding is completed with determination of distinct, uniform, and stable (DUS) status confirmed.

Cultivation of the variety does not require special conditions or treatments.

2

The variety is currently mainly intended for fruit production.

SUMMARY OF THE VARIETY

The new mandarin plant 'Mikanken15' has leaf blades with very small ratio length/width, short petiole length, very short length of petal, which distinguish 'Mikanken15' from its female parent 'HAREHIME'.

Also, the new mandarin plant 'Mikanken15' having absent or sparse density of spines, and short petiole length and very short length of petal, distinguish it notably from the comparative variety 'SEINANNOHIKARI' (not patented in the U.S., plant variety protection granted in Japan, PVP No. 17,969).

A comparison with the male parent 'Ehime17' is not available because 'Ehime17' was an old breeding line, whose states of characteristics are unknown and for which there are no long living plant materials.

A comparison with both 'HAREHIME' and 'SEINANNOHIKARI' is as follows (evaluation based on averages):

TABLE 1

Characteristics	Reference variety 'HAREHIME'	Reference variety 'SEINANNOHIKARI'	Present variety 'Mikanken 15'
Tree: Density of spine	Absent or sparse	Dense	Absent or sparse
Leaf blade: ratio length/width	Medium (2.3)	Very small (1.9)	Very small (2.0)
Petiole: length	Long (2.0 cm)	Medium (1.5 cm)	Short (1.3 cm)

TABLE 1-continued

Characteristics	Reference variety 'HAREHIME'	Reference variety 'SEINANNOHIKARI'	Present variety 'Mikanken 15'
Flower: length of petal	Short (12.5 mm)	Short (13.6 mm)	Very short (7.2 mm)

BRIEF DESCRIPTION OF THE DRAWINGS

In the accompanying drawings, which are as nearly true as is reasonable possible to make in a color illustration of this type:

FIG. 1 is a color photograph showing a general view of the mandarin plant 'Mikanken15' bearing fruits.

FIG. 2 is a color photograph showing flowers of 'Mikanken15'.

FIG. 3 is a color photograph showing leaves of 'Mikanken15';

FIG. 4 is a color photograph showing fruits of 'Mikanken15'.

FIG. 5 is a color photograph showing the flowers of 'Mikanken15' and the comparative varieties 'HAREHIME' and 'SEINANNOHIKARI', illustrating the difference in the lower length of petals.

Due to chemical and/or digital development, processing and printing, the plants or portions of plants depicted in the photographs may or may not be precisely accurate, when compared to the actual botanical specimens.

DETAILED DESCRIPTION OF THE INVENTION

The botanical description and the photographs are of the 'Mikanken15' plants evaluated in 2023 and 2024 (including for the comparison with the reference plants 'HAREHIME' and 'SEINANNOHIKARI'). The values provided are averages.

The plants shown on the photographs were grown at Uwajima, Ehime, Japan. The plant is a 10-year old plant grown after top grafting. The tree was photographed on Dec. 3, 2023, the flowers were photographed on Apr. 25, 2024, the mature leaves were photographed on Dec. 17, 2023, and the fruit were photographed on Dec. 3, 2023. The botanical description below is that of a 10-year old plant.

Colors are given according to the Colors are given according to the J.H.S. (Japan Horticultural Society) Color Chart. (2nd edition 1997 reprint).

BOTANICAL DESCRIPTION

TABLE 2

Characteristics	States	Values
Ploidy	Diploid	
Tree: height		3.6 m
Tree: spread		3.5 m
Tree: trunk diameter (10 cm above the graft location)		23 cm
Trunk texture	Rough	
Crotch angle		62°

TABLE 2-continued

Characteristics	States	Values
Tree: growth habit	Spreading	
Tree: density of spines	Absent or sparse	5.3
Tree: length of spines		0.3 cm
Branch: length		7.5 mm
Branch: diameter		2.9 mm
Branch: texture	Smooth	
10 Leaf blade: length (apical leaflet in case of compound leaf)	Medium	9.5 cm
Leaf blade: width (as for No. 5)	Medium	4.8 cm
Leaf blade: ratio length/width (as for No. 5)	Very small	2.0
15 Leaf blade: shape in cross section (as for No. 5)	Intermediate	
Leaf blade: twisting	Absent or weak	
Leaf blade: blistering	Absent or weak	
Leaf blade: green color	Medium	
Leaf blade: undulation of margin	Absent or weak	
Leaf blade: incisions of margin	Absent	
Leaf blade: shape of apex	Acute	
Leaf blade: emargination at tip	Absent	
Petiole: length	Short	1.3 cm
Petiole: presence of wings	Present	
25 Varieties with petiole wings present only: Petiole: width of wings	Narrow	2.9 mm
Flower: diameter of calyx		0.6 cm
Flower: length of petal	Very short	7.2 mm
Flower: width of petal	Medium	5.3 mm
Flower: ratio length/width of petal		1.4
30 Flower: length of stamens		4.7 mm
Anther: color	Light yellow	JHS 2202
Style: length		4.5 mm
Infructescence: clustering of fruits	Present	
Fruit: length		4.6 cm
Fruit: diameter		7.9 cm
35 Fruit: ratio length/diameter	Medium	1.72
Fruit: position of broadest part	At middle	
Fruit: shape in transverse section	Circular	
Fruit: general shape of proximal part (excluding neck, collar and depression at stalk end)	Flattened	
Fruit: presence of neck	Absent	
40 Only varieties without fruit neck: Fruit: presence of depression at stalk end	Present	
Only varieties without fruit neck:		4.3 mm
Fruit: depth of depression at stalk end		
Fruit: presence of constriction at stalk end	Absent	
45 Fruit: number of radial grooves at stalk end	Intermediate	
Fruit: length of radial grooves at stalk end		9.6 mm
Fruit: presence of collar	Absent	
50 Fruit: abscission layer between floral disc and fruit	Absent or weakly developed	
Fruit: general shape of distal part (excluding nipple, bulging of navel and depression at distal end)	Flattened	
Fruit: presence of depression at distal end	Present	
Fruit: depth of depression at distal end		2.1 mm
Fruit: diameter of depression at distal end		32.4 mm
55 Fruit: presence of areola	Incomplete	
Fruit: Type of areola	Smooth	
60 Fruit: Diameter of areola		1.7 cm
Fruit: diameter of stylar scar		2.1 mm
Fruit: persistence of style	None	
Fruit: presence of navel opening	Absent	
Fruit: presence of radial grooves at distal end	Absent	

US PP37,207 P2

5

TABLE 2-continued

Characteristics	States	Values
Fruit surface: predominant color(s)	Medium orange	JHS 1605
Fruit surface: glossiness	Medium	
Fruit surface: roughness	Smooth	
Fruit surface: size of oil glands	All more or less the same size	
Fruit surface: size of larger oil glands	Small	
Fruit surface: conspicuousness of larger oil glands	Strong	
Fruit surface: presence of pitting and pebbling on oil glands	Pitting and pebbling absent	
Fruit rind: thickness	Thin	2.2 mm
Fruit rind: adherence to flesh	Weak	
Fruit rind: strength	Medium	
Fruit rind: oiliness	Dry	
Fruit rind: conspicuousness of oil glands on inner surface	Absent or weakly conspicuous	
Fruit: color of albedo	White	JHS 2502
Fruit: density of albedo	Loose	
Fruit: amount of albedo adhering to flesh (strands excluded)	Small	
Fruit: presence of albedo strands	Present	
Fruit: Amount of albedo strand	Medium	
Fruit: main color of flesh	Dark orange	JHS 1607
Fruit: filling of core	Sparse	
Fruit: diameter of core	Large	
Fruit: presence of rudimentary segments	Absent or very weak	
Fruit: number of well-developed segments	15	

6

TABLE 2-continued

Characteristics	States	Values
5 Fruit: coherence of adjacent segment walls	Medium	
Fruit: strength of segment walls	Weak	
Fruit: length of juice vesicle	4.0 mm	
Fruit: thickness of juice vesicles	2.3 mm	
Fruit: conspicuousness of juice vesicle walls	Medium	
10 Fruit: coherence of juice vesicles	Medium	
Fruit: presence of navel (viewed internally)	Absent or very rare	
Fruit: juiciness	High	
Fruit juice: total soluble solids	High	14.9
Fruit juice: acidity	Low	0.91
Fruit: strength of fiber	Weak	
Fruit: number of seeds (open pollination)	Absent or very few	0
Seed: polyembryony	Absent	
Time of maturity of fruit for consumption	Very early to early	January
20 Fruit: parthenocarpy	Present	
Fruit productivity (pounds or bushels per acre)	Not examined	

Other features of the plant are as follows:

Disease and pest resistance: Not observed to date.

Tree hardiness: USDA Hardiness Zone 9b.

The invention claimed is:

1. A new and distinct variety of *Citrus* plant named 'Mikanken15', substantially as described and illustrated herein.
